US0D1064660S

(12) **United States Design Patent** (10) **Patent No.:** **US D1,064,660 S**
(45) **Date of Patent:** **** Mar. 4, 2025**

(54) **CUSHION**

(71) Applicant: **Xiaoming Xie**, Jieyang (CN)

(72) Inventor: **Xiaoming Xie**, Jieyang (CN)

(**) Term: **15 Years**

(21) Appl. No.: **29/791,250**

(22) Filed: **Jan. 6, 2022**

(51) **LOC (15) Cl.** **06-09**

(52) **U.S. Cl.**

USPC **D6/601**

(58) **Field of Classification Search**

(57) **CLAIM**

The ornamental design for a cushion, as shown and described.

DESCRIPTION

FIG. 1 is a first perspective view of a cushion showing my new design;

FIG. 2 is a second perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof;

FIG. 9 is an enlarged view of the selected portion in FIG. 1; and,

FIG. 10 is an enlarged view of the selected portion in FIG. 2.

The dot-dash broken lines in FIGS. 1, 2, 9, and 10 depict boundary lines of the enlarged views and form no part of the claimed design.

1 Claim, 10 Drawing Sheets
